UNITED STATES PATENT OFFICE.

SAMUEL GRUNDY FORST, OF TORONTO, ONTARIO, CANADA.

OIL AND GAS BURNER.

1,172,269.

Specification of Letters Patent. Patented Feb. 22, 1916.

Application filed June 22, 1915. Serial No. 35,522.

To all whom it may concern:

Be it known that I, SAMUEL GRUNDY FORST, a citizen of the United States, residing in the city of Toronto, county of 5 York, Province of Ontario, Canada, have invented certain new and useful Improvements in Oil and Gas Burners, of which the following is a specification.

My invention relates to improvements in 10 oil and gas burners, and the objects of my invention are firstly, to construct a device of the class described which will be simple in construction, and easily taken apart to permit the same to be cleaned when necessary, and the component parts of which 15 can be assembled without the employment of screws or bolts and the like; secondly, to provide a device which while cheap to manufacture is yet durable and efficient; thirdly, 20 to construct a device of this class with an inner annular chamber so as to permit gas to pass thereinto from the generator to "superheat" a quantity of the gas, so to speak so that this "superheated gas" will 25 raise the temperature of the mixing air and gas within the flue of the device high enough to consume any smoke that may be in the flue, and fourthly, to design a device of this 30 class which can be used to burn ordinary illuminating or heating gas, and the preferred construction of my device will be 35 hereinafter particularly set forth and what I claim as new will be pointed out in the claims.

Figure 1 is a perspective view of my preferred form of device, and Fig. 2 is a vertical central section through the same, showing the device mounted in a suitable fire box which is also shown in section.

In the drawings:—A is any suitable 40 priming basin, provided with a threaded hub B through which screws the threaded lower end of the feed pipe C. The said feed pipe is suitably coupled to any suitable coupling D which leads to a source of 45 fuel supply, not shown. The said priming basin is provided with a plurality of lugs E, preferably notched as shown at F to support the base member G of the flue H. 50 The inner corner I of said base member G is preferably chamfered as shown, so as to permit the air to readily pass up into said flue. The top edge J of the priming basin A is spaced below the bottom of the base 55 member G so as to provide a passage-way a for the air. The threaded hub B is pref-

erably provided with a plurality of air holes K. Resting upon the base member G is the upper member L of the flue H. The inner lower edge of the upper member L is preferably chamfered as shown at 2 and rests upon the outer upper chamfered edge 3 of the base member G. Depending below the upper member L are a plurality of lugs 4 which overlap portion of the base member G. The construction just described is that which I preferably use to support the upper member L in proper relationship to the base member G. As illustrated in the drawings, the flue H is preferably tapered so that the 60 upper end thereof is of less diameter than the base of the flue, to assist in the creating of a draft therethrough. Carried by the upper end of the feed pipe C is a sleeve 5 which surrounds said feed pipe. The internal bore of said sleeve is greater than the external diameter of said feed pipe, thereby providing an annular chamber 6. The said sleeve is preferably provided with a conical base 7, and resting upon said base and housing the said sleeve 5 is the generator 8. The said generator is preferably integrally provided with a plurality of spacing lugs 9 which are designed to prevent any undue lateral displacement of the said generator in 70 respect of the sleeve 5.

As is usual in a device of this class, the priming basin is utilized to initially generate heat to heat the generator and other parts of the device. When the device is 90 first started, the liquid oil passes through the hole 10 formed in the plugged upper end 11 of the feed pipe C, and flows over the top and down the sides of the sleeve 5. As the device becomes thoroughly heated, 95 gas is formed within the pipe C and escapes through the hole 10 into the generator 8, and the same escapes from said generator at its lower end through the passage ways 12 formed in the inner lower edge of the base 100 of the generator. As the gas escapes through said passage-ways into the flue, it mixes with the air passing into said flue through the air openings described, and the mixture is ultimately consumed.

The bore of the lower portion 13 of the generator 8 is of greater diameter than the rest of the bore of the generator, thus providing an expansion chamber at the base of said generator, thus permitting 110 of the rapid escape of the generated gas from the upper portion of said gen-

erator. The passage-ways 12 are quite small, and the result is that the gas in the said expansion chamber shall be raised to the desired temperature by the time it escapes through the said passage-ways.

Formed in the sides of the sleeve 5 are one or more holes 14, positioned within the lower portion 13 of the said generator, and the function performed by said holes is to 10 permit gas to escape from the said expansion chamber into the annular chamber 6. This gas naturally becomes ignited within the said annular chamber, and so assists in vaporizing the oil in the feed-pipe C. The 15 burning gas within said annular chamber 6 can only escape therefrom through the opening 15 formed in the conical base 7, and it naturally follows that as a result of the commingling of the burning gases 20 from the said chamber 6, with the burning gases in the flue H, the temperature of the air and gases within the said flue will be raised high enough to consume any smoke that may result from the combustion of the 25 gas passing through the passage-ways 12.

The preferred shape of the base 7 facilitates the escape of gas from the expansion chamber formed in the lower portion 13 of the generator 8.

30 The construction described particularly in respect of the feed pipe C and the threaded hub B enables me to adjust the position of the device in respect of the top of the stove, not shown.

35 In Fig. 2 I show my device mounted within the fire box 16 of any suitable stove. In order that my device operate properly, I must place a plate 17 around the base member G, and this plate should fit the fire 40 box. Since the said plate rests against the flange 18 of the base member G, no draft can escape by said plate to impair the action of my device.

45 From my experiments I have found that I can use my device as a gas burner. That is to say, ordinary illuminating or heating gas can be piped to my burner and consumed therein.

50 While I have described what I consider to be the best embodiment of my invention, I desire it to be understood that the principle can be embodied in different forms, and I desire not to be limited beyond the requirements of the prior art and the terms 55 of my claims.

What I claim as my invention is:

1. A gas-generating oil-burner comprising a feed-pipe provided with a hole in its upper end; a hole-provided sleeve supported 60 by said feed-pipe and surrounding the same, the internal bore of said sleeve being greater than the external diameter of said pipe; a conical base for said sleeve; a generator surrounding said sleeve and resting upon said conical base, and provided with

one or more passage-ways facing said conical base to permit the escape of gas; the diameter of the bore of said generator being greater than the external diameter of said sleeve; a priming basin carried by the lower 70 end of said feed pipe; a flue surrounding said generator, and means whereby said flue is removably supported above said priming basin to provide air openings; a portion of the gas formed in said generator 75 passing through the holes formed in said sleeve into said sleeve, for the purpose specified.

2. A gas-generating oil-burner comprising a feed-pipe provided with a hole in its 80 upper end; a hole-provided sleeve supported by said feed-pipe and surrounding the same, the internal bore of said sleeve being greater than the external diameter of said pipe to form an annular chamber within 85 said sleeve; a conical base for said sleeve; a generator surrounding said sleeve and resting upon said conical base, and provided with one or more passageways facing said conical base to permit the escape of gas; the 90 diameter of the bore of said generator being greater than the external diameter of said sleeve, and the bore of the lower portion of said generator being greater than the bore of the rest of the generator to form an ex- 95 pansion chamber into which open the holes formed in said sleeve so that a portion of the gas in said expansion chamber may escape into said annular chamber through said holes and out of said annular chamber 100 at the lower end thereof; a priming basin carried by the lower end of said feed pipe; a flue surrounding said generator, and means whereby said flue is removably supported above said priming basin to provide air open- 105 ings.

3. A gas-generating oil-burner comprising a feed-pipe provided with a hole in its upper end; a hole-provided sleeve supported by said feed pipe and surrounding the same, the 110 internal bore of said sleeve being greater than the external diameter of said pipe to form an annular chamber within said sleeve; a conical base for said sleeve; a generator surrounding said sleeve, and resting upon 115 said conical base, and provided with one or more passageways facing said conical base to permit the escape of gas; the diameter of the bore of said generator being greater than the external diameter of said sleeve, 120 and the bore of the lower portion of said generator being greater than the bore of the rest of the generator to form an expansion chamber into which open the holes formed in said sleeve so that a portion of the gas 125 in said expansion chamber may escape into said annular chamber through said holes and out of said annular chamber at the lower end thereof; a priming basin carried by the lower end of said feed pipe; a flue surround- 130

ing said generator, composed of a base member, and an upper member removably supported upon said base member and means whereby said flue is removably supported above said priming basin to provide air openings.

4. A gas-generating oil-burner comprising a feed-pipe provided with a hole in its upper end; a hole provided sleeve supported by 10 said feed pipe and surrounding the same, the internal bore of said sleeve being greater than the external diameter of said pipe to form an annular chamber within said sleeve; a conical base for said sleeve; a generator 15 surrounding said sleeve and resting upon said conical base, and provided with one or more passageways facing said conical base to permit the escape of gas; the diameter of the bore of said generator being greater than 20 the external diameter of said sleeve, and the bore of the lower portion of said generator being greater than the bore of the rest of the generator to form an expansion chamber into which open the holes formed 25 in said sleeve so that a portion of the gas in said expansion chamber may escape into said annular chamber through said holes and out of said annular chamber at the lower end thereof; a priming basin carried by the 30 lower end of said feed pipe; a flue surrounding said generator, composed of a base member, and an upper member removably supported upon said base member, and an exteriorly-placed annular flange carried by 35 said base member.

5. In a gas-generating oil-burner, the combination with a feed pipe; gas-generating means housing said feed pipe and supported thereby, and a priming basin screwed onto 40 the lower end of said feed pipe, of a flue sur-

rounding said gas generating means comprising a tubular base member having a chamfered upper-outer corner, and an upper tubular member having an inner chamfered corner at its lower end which rests against the chamfered corner of said base; a plurality of lugs carried by said upper member and overlapping said base member, and means carried by said priming basin for removably supporting said flue above the top 50 edge of said priming basin to provide air passages.

6. A gas-generating oil-burner comprising a feed pipe provided with a hole in its upper end; a hole-provided sleeve supported 55 by said feed pipe and surrounding the same, the internal bore of said sleeve being greater than the external diameter of said pipe; a generator surrounding said sleeve, means for supporting the lower end of said generator, which lower end is provided with one or more passage-ways facing said supporting means to permit the escape of gas from said generator; the diameter of the bore of said generator being greater than the external diameter 60 of said sleeve; a priming basin carried by the lower end of said feed pipe; a flue surrounding said generator, and means whereby said flue is removably supported above said priming basin to provide air 65 openings; a portion of the gas formed in said generator passing through the holes formed in said sleeve into said sleeve for the purpose specified.

In testimony whereof I have affixed my 70 signature in presence of two witnesses.

SAMUEL GRUNDY FORST.
